UNITED STATES PATENT OFFICE.

ALBERT DE LASKI, OF LYNN, MASSACHUSETTS.

CIRCULAR LOOM.

SPECIFICATION forming part of Letters Patent No. 375,135, dated December 20, 1887.

Application filed October 15, 1885. Serial No. 179,960. (No model.)

To all whom it may concern:

Be it known that I, ALBERT DE LASKI, of Lynn, in the county of Essex and State of Massachusetts, have invented certain new and 5 useful Improvements in Circular Looms, of which the following is a specification.

This invention consists in certain improvements in circular looms relating to the means for impelling the shuttles, the heddle motion, 10 and other details, all as described and claimed hereinafter.

Of the accompanying drawings, forming a part of this specification, Figure 1 represents a vertical central section of portions of a circular loom, showing the shuttle-operating mechanism, the heddles and a part of their operating mechanism being omitted. Fig. 1^a represents a section on line $x'x'$, Fig. 1. Fig. 2 represents a top view of a part of the shuttle-driving mechanism. Fig. 3 represents a top view, partly sectioned, of a portion of the loom, showing the heddle-operating mechanism, certain features being omitted for the sake of clearness. Fig. 4 represents a section on line 25 $x x$, Fig. 3, looking toward the right; Fig. 5, a side view of the parts shown in sectional end elevation in Fig. 4, excepting the beam. Fig. 6 represents a side elevation of the feed-rolls and their operating mechanism, with parts 30 of the supports for the latter in section. Fig. 7 represents a section on line $y y$, Fig. 6, looking toward the left. Fig. 8 represents a top view, and Fig. 9 an end view, of the feed-rolls and connected parts.

35 The same letters of reference indicate the same parts in all the figures.

In the drawings, a represents the circular track or race on which the shuttles b move. Said track is supported by vertical standards c . 40 Each shuttle consists of a frame, 2, a bobbin, 5, journaled in said frame, and wheels 3 3' 4, adapted to run on the circular track a , the wheels 3 3' at the outer side of the carriage being larger than the wheel 4 at the inner side. The weft-thread from the bobbin 5 passes through a tubular guide, 6, in the inner side of the shuttle-frame, and therefore acts to hold the inner side of the shuttle down upon the track a . The tubular guide 6 also forms 45 the journal for the wheel 4.

Each shuttle is driven by means of a friction-wheel, d , which is rotated while in contact with one of the wheels 3, and is moved over the cir-

cular track a , so as to impart a continuous movement to the shuttle, each wheel d having 55 a planetary motion. The arbors e , to which the wheels d are affixed, are journaled in bearings in arms f , radiating from a head, i , which is journaled in a frame or spider, g , supported by the standards $c c$. Said head is provided 60 with a bevel-gear, h , with which meshes a similar gear, j , on a driving-shaft, k , the head i being thus rotated and caused to carry the friction-wheels around over the circular track. The friction-wheels are positively rotated 65 while they are being thus carried over the track by means of bevel-gears $l l$, affixed to the arbors $e e$, and a bevel-gear, m , affixed to the frame or spider g . The progressive circular movement imparted to the arbors $e e$ by the 70 rotation of the head i , in connection with the gears $l l$ and fixed gear m , causes the arbors and their friction-wheels to rotate. The arm f has a loose pulley, d' , which runs on one of the outer wheels, 3, of the shuttle. (See Fig. 2.) 75

The described mechanism for impelling the shuttles constitutes an important part of my invention, and is distinguished from mechanism heretofore used for the purpose by its simplicity and freedom from liability to derangement and breakage. The fixed gear m , that rotates the arbors of the friction-wheels, is located between said wheels and the center, about which they move on the track, the arbors extending inwardly from the friction-wheels. 80 Heretofore in this class of looms said arbors have extended outwardly from the friction-wheels and have been rotated by a large fixed gear surrounding the space in which the friction-wheels were located. Said arrangement 85 involves much greater friction between the fixed gear and the gears on the arbors, as well as greater liability of breaking the teeth of said gears than is met with in my improved loom.

90 The warp-threads pass from a series of beams, e' , journaled in bearings on the supporting frame through guides o^3 , and from thence through the heddles to the central tube, where the warp and woof threads are interwoven to 95 form the tubular fabric, the latter being drawn through the tube by suitable means, as herein-after described. The shuttles pass, as usual, through the shed formed by the raised and depressed woof-threads, the wheels of the shuttles, 100 passing over the depressed threads, while the 105

raised threads pass between the friction-wheels and the shuttle-wheels, as shown in Fig. 1.

The heddle-frames o o' are arranged in pairs 5 and in a circular series, as usual, and move on vertical rods q q , affixed to the supporting-frame. The lower portions of the heddle-frames in each pair are connected by straps or chains p p , passing around loose pulleys r , 10 which, with their supporting-brackets S S' , are vertically adjustable. Such adjustment is secured by providing each bracket with an externally-threaded depending spindle, S' , which engages a vertically-threaded recess in a socket, S , secured to and projecting from the heddle-frame supports. A nut, S^3 , engages the 15 projecting portion of each spindle S' and locks it in its adjusted position.

The upper portions of the heddle-frames of 20 each pair are connected by chains t t , passing over and engaged with sprocket-wheels u on arbors v , journaled in bearings on the supporting-frame. Said arbors are rocked or rotated alternately in opposite directions by 25 means of reciprocating racks w , fitted to slide in guides on the frame, and pinions a' , affixed to the arbors v . The racks w are provided with extension-bars w' , having studs or rollers b' on their inner ends entering a grooved cam, 30 c' , affixed to the head i' . Said cam is formed so that when it is rotated it simultaneously retracts the racks at one side and projects those at the opposite side, as shown in Fig. 3. The movements thus imparted to the racks w 35 and arbors v cause the sprocket-wheels n and chains t to reciprocate the heddles, the heddles of each pair being moved simultaneously in opposite directions, as usual. The ends of the wires of the heddles are inserted in slots 40 d d' , cut in the heddle-frames, said slots being made in two series, as shown in Fig. 5.

Each beam c' that supplies the warp-threads is provided with a brake composed of a cord, f' , secured at one end to the frame and passed 45 around the end of the beam, its other end being attached to a rod, g' , which is pressed by a spring, h' , so as to cause the cord f' to bind upon the periphery of the beam end. The woven tubular fabric is grasped and drawn 50 along, so as to keep the proper tension on the warp-threads, by means of rolls h h' , journaled in bearings i and driven by a connection being shown as a bevel-gear, k' , on the shaft k , 55 a vertical shaft, l' , having a bevel-gear, m' , meshing with the gear k' , a horizontal shaft, m , connected by gears n o' with the shaft l' , and the gears p q r' , whereby motion is communicated from the shaft m to the arbor of 60 one of the rolls h , the arbors of the two rolls being connected by gears s' .

The gear p is mounted on shaft m . The gear q is mounted on a stud on a lever, t' , pivoted to said frame, so that it can be moved to 65 throw the gear q into and out of engagement with the gear r' .

By reference to Fig. 7 it will be noted that

t^2 designates a slotted arm extending integrally from the lever t' , and the said arm and the slot therein are curved concentric with the pivot 70 of the lever t' . One of the frame-supports is provided with an arm, t^5 . The lever-arm is designed to move in close proximity to the arm t^5 , so that a bolt, t^6 , on the latter will play along the curved slot in the arm t^2 as the lever t' is raised or depressed. A nut, t^4 , engaging the threaded end of the bolt, is designed to rigidly lock the bolt t^6 at any desired point along said slot, so that the lever t' may be rigidly secured in any position to which it may 75 be moved. By such construction the gear-wheel q' may be rigidly locked in engagement with the gear-wheel r' . The gear r' is provided with a hub, v' , adapted to slide on the arbor a^2 of one of the rolls h' . One end of 80 said hub is formed as a clutch member to engage a corresponding member, b^2 , affixed to the arbor a^2 . A spring, c^2 , normally holds the two members in engagement, as shown in Fig. 6. A lever, d^2 , pivoted at e^2 to the supporting-frame, is engaged with the hub of the gear r' by means of rollers on the lever entering a groove in the hub, Fig. 8, so that a movement of the lever against the pressure of the spring c^2 will separate the clutch members, and therefore stop the rotation of the rolls h' . A hand-wheel, g^2 , is attached to the arbor a^2 , so that the rolls can be rotated by hand when desired. When this is done, the gear q' is thrown 90 out of engagement with the gear r' by means 95 of the lever t' .

The rolls h' are grooved at k^2 k^2 , said groove receiving the edges of the flattened woven tube which passes between the rolls, so that said edges are not creased by the rolls. 100

One of the principal uses of my improved loom is to weave a covering upon a tube of rubber which is passed through a tubular guide, a^3 , within the head i and a tubular weaving-pin, b^3 , secured to the lower end of 110 said guide.

To guide the rubber tube and prevent it from twisting I provide at a suitable point within the tubular guide or within the weaving-pin (preferably the latter) a guide or projection, c^3 , which causes the rubber tube e^3 to assume a horseshoe form in cross-section before it enters the tubular woven covering. 115

It will be seen that the guide or projection c^3 prevents the tube from turning or twisting, and thus insures its delivery in a straight condition into the woven covering. The tube is subsequently expanded by steam and caused to adhere to the woven covering. 120

I claim—

1. The combination of the circular track a , a shuttle adapted to travel thereon, outer wheels, 3 3 , on said shuttle, and inner wheel, 4 , all of said wheels bearing directly upon the track, a head, i , gearing for rotating the same, 130 a horizontal radial arm, f , an arbor mounted in bearings in said arm, gearing for rotating said arbor from the rotary movement of the head, and a friction-wheel, d , located on the

outer end of the arbor and bearing directly upon the periphery of one of the wheels 3, and a second friction-wheel, d^3 , mounted on the arm f and bearing directly upon the periphery 5 of the other wheel 3, substantially as set forth.

2. The combination of the heddle and heddle-frames and the heddle-operating mechanism, consisting of the arbors connected, as described, with the heddle and heddle-frames, 10 and provided with pinions, the radiating racks engaged with said pinions, and the cam and means for rotating it, whereby said racks are reciprocated, as set forth.

3. The combination of the circular track a , 15 a shuttle adapted to travel thereon and provided with a wheel, 3, on its outside and with a tubular guide, 6, on its inner side, a wheel, 4, mounted on said guide, a head, i , gearing for rotating said head, and devices for driving 20 said shuttle from said head, substantially as set forth.

4. The combination, with the race, shuttle, heddles, heddle-frames, beams, and operating devices for said shuttle and heddle-frames, of 25 a tubular weaving-pin, b^3 , having an internal projection, a pair of horizontal rolls for receiving the fabric from said weaving-pin, gearing for driving said rolls to feed the fabric, a gear-wheel mounted on the shaft of one of said rolls, 30 and a clutch device for permitting the engagement and disengagement of said gear-wheel and roller-shaft, substantially as set forth.

5. The combination, with the race, shuttle, heddles, heddle-frames, beams, and operating

devices for said shuttle and heddle-frames, of 35 a tubular weaving-pin, b^3 , having an internal projection, a pair of horizontal rolls geared together and receiving the fabric from said weaving-pin, a driving-gear, r' , a driving means, a lever, t' , provided with a gear-wheel, 40 q' , rotated by said driving means and adapted to be moved by said lever into and out of mesh with the wheel r' , and devices for locking said lever in an engaged or disengaged position, substantially as set forth. 45

6. The combination, with a weaving-pin, b^3 , internal projection, c' , therein, and devices, substantially as described, for weaving a tubular fabric, of a pair of feed-rolls adapted to receive a tubular fabric and provided with peripheral grooves to accommodate the edges of 50 said fabric, substantially as set forth.

7. The combination, with a tubular weaving pin or guide, of devices, substantially as described, for weaving a tubular fabric at the 55 end of said pin or guide, and an internal projection located on one side in said pin or guide for bending the woven tube, substantially as set forth.

In testimony whereof I have signed my name 60 to this specification, in the presence of two subscribing witnesses, this 6th day of October, 1885.

ALBERT DE LASKI.
